UNITED STATES PATENT OFFICE

2,441,686

VIBRANT ARMATURE MASSAGER

Henry B. Cohen, New York, N. Y., assignor to
 The Lektron Corporation, New York, N. Y., a
 corporation of New York

Application February 3, 1947, Serial No. 726,164

3 Claims. (Cl. 128—41)

1

This invention relates to mechanical beauty aids or the like, and is more specifically directed to a motor driven vibrator for massaging the skin. The general object of this invention is to provide a motor driven vibrator which can be used with beneficial effect on the face and other delicate portions of the skin for the purpose of providing a light massage for stimulating circulation and beautifying the skin without any rough action or harmful rubbing effects.

A more specific object of this invention is to provide a motor driven vibrator which will impart a rapid succession of light pats onto the skin and which can be driven about the face or other part of the body to which it is applied without creating any rubbing action thereon.

Another object of this invention is to provide a motor driven vibrator wherein the elements which come into contact with the skin and which apply the massage thereto comprise a number of rollers which are reciprocated in a rapid succession of small alternating displacements away and toward the skin but are left free to rotate about their axes and to develop on the skin as the vibrator is being moved about without causing friction and harmful irritating action thereon.

A further object is to provide a vibrator of the character described achieving the foregoing object, and wherein the aforementioned rollers are supported for rotation in a member which is vibrated but is held against any motion other than vibration.

A still further object is to provide a vibrator of the character described, achieving the above stated objects, and which is furthermore extremely simple in construction, efficient, inexpensive and easily operated.

A still further object is to provide a vibrator of the character described, achieving the above stated objects which is electrically driven and yet is completely safe and will not cause electric shock or other harmful or disagreeable electric phenomena.

This invention will be best understood by a reference to the appended drawings, illustrating one preferred embodiment of the invention, in which:

Fig. 1 is a side view of a vibrator according to this invention.

Fig. 2 is a longitudinal cross-section taken along the axis of the device at right angles to the plane of Fig. 1, with the patter rollers and part of their support shown in view.

Fig. 3 is a cross-section taken along line 3—3 of Fig. 2 looking in the direction of the arrows.

2

Fig. 4 is a partial cross-section of the device taken along the line 4—4 of Fig. 2 looking in the direction of the arrows.

Fig. 5 is a cross-section of the device taken along the line 5—5 of Fig. 2 looking in the direction of the arrows.

Fig. 6 is a cross-section of the device taken along the line 6—6 of Fig. 2 looking in the direction of the arrows.

10 Fig. 7 is a perspective view of one component element of the device.

Referring now in detail to the drawings, 10 designates a housing preferably knurled or otherwise suitably finished for easy grip, which forms the handle of the vibrator and in which are enclosed the driven elements of the device. The housing is closed at one end by a knob 11 having an opening to admit a cord 9, connected to a plug, not shown, and conveying electric current to the operating elements of the device.

15 13 is a support for two rollers 14 designated herein-after as "patter rollers." The patter rollers are freely supported in any suitable manner, for instance, as disclosed, by making them rigid or solid with bearing studs 15 which engage depressions 16 in upstanding arms 17 of support 13. In the embodiment illustrated there are two rollers, therefore there are four arms 17 which are rigid or solid with a yoke 18 and together

20 with said yoke constitute the support 13. Said support 13 is rigidly attached to an armature 19, for instance by means of the arrangement shown in the drawings. Said arrangement comprises a screw 20 screwing into a square member 21 and clamping the support 13 and a washer 22 thereto.

25 35 The armature 19 is provided with a threaded upper portion 23 which also screws into member 21. A washer 24 is clamped between said square member 21 and the armature 19. The square guide member 21 penetrates through a correspondingly shaped opening 25 in a cap 26 which is fitted on top of the housing 10. Two resilient elements 27 and 28, herein disclosed as coil springs, are comprised respectively between the washer 24 and the cap 26, and between the washer 24 and the armature 19. The square

40 45 50 guide member 21 penetrates through a correspondingly shaped opening 25 in a cap 26 which is fitted on top of the housing 10 and is centrally bored to allow the passage therethrough of the armature 19. Said disc separates the space comprised by housing 10, knob 11, and cap 26, into two chambers, which may be defined as the "solenoid chamber" below disc 29, and the "spring chamber," above said disc.

The portion of the armature 19 which penetrates into the housing 10 is surrounded by sole-

noid coil 30 which extends substantially for the whole length of the housing. Internally of the coil 30 and surrounding the armature 19 is a sleeve 31, herein disclosed as a thin cylindrical member, preferably of brass or other like metal, which is rigidly connected to disc 29, as by force-fitting or brazing or in any other suitable manner, and which is cut lengthwise to provide a slot 32. The end of sleeve 31 opposite to that which is connected to disc 29 passes through spacing washers 33 and 34, insulating disc 35, and washer 36, and is flared outwardly to help retain the said washers and disc. A core 37 is provided in the center of the lower part of the housing 10 within the sleeve 31, and is retained within said sleeve in predetermined longitudinal positioned relationship by the engagement of a pin 38 with slots 39 in the sleeve 31.

The electrical connections of the device are best shown in Fig. 6. The two component wires 40 of the cord 9 pass upwardly through slots 41 of the insulating disc 35, then downwardly again through slots 42. The end portions of said wires 40 are then stripped of their insulation and pass upwardly again through bores 43 of disc 35. Above said bores they are soldered, as at 44, to lead wires 45 of coil 30.

The device operates as follows. The sinusoidal impulses of the alternating current fed through the wires 40 and the wires 45 to the coil 30 produce a pulsating magnetic field within the space enclosed by the coil 30. Said field induces pulsating magnetism in the core 37 which sets the armature 19 in vibrating motion. This motion is amplified by the action of opposing springs 27 and 28, which are designed to match the frequency of the feed current, whereby to achieve a smooth and effective vibration of the armature with a limited size of solenoid, and which also prevent any sharp blows from occurring between the armature and the stationary parts of the vibrator. The engagement of square guide member 21 with the corresponding opening of cap 26 prevents the armature 19 from rotating about its axis, and thereby from transmitting to said roller support 13 any motion other than the desired vibration. This maintains the axis of the patter rollers in invariable orientation with respect to the handle 10. The patter rollers 14 with their support 13 vibrate with the armature, and thus impart to the skin a succession of light pats achieving the massage effect desired. As the vibrator is manually driven about the area to be massaged, the patter rollers rotate freely with respect to their support 13, thereby eliminating any harmful or undesirable rubbing effect on the skin, and rendering the device suitable for massaging even the most delicate portions of the body.

While I have described a preferred embodiment of my invention by way of illustration, I want it understood that I am not limited to the exact details herein set forth, and that my invention embraces any modifications and variations which fairly fall within the scope of the appended claims.

I claim:

1. A mechanical beauty aid, comprising a casing, a solenoid coil housed therein, a metallic core located internally of said coil and in fixed positioned relationship therewith, means for conveying an electric current through said coil, an armature mounted in said housing for vibration parallel to the axis of said solenoid and extending in opposing relationship to said core, a mem-

ber rigid with said armature and extending outwardly of said casing through an opening thereof, a flange rigid with said armature, two springs engaging said flange on opposite faces thereof and resiliently reacting to the vibrations of said armature, a number of patter rollers, and a support rigid with said outwardly extending member for said rollers, each of said rollers being so mounted in said support as to be freely rotatable with respect thereto about an axis perpendicular to the direction of the vibrations of said armature.

2. A mechanical beauty aid, comprising a casing embodying an open cylindrical member, a closure member rigidly connected to one end of said cylindrical member and having an opening therein for two conductors, and a cap rigidly connected to the other end of said cylindrical member; a disc rigidly mounted internally of said casing and dividing the space enclosed by said casing into a solenoid chamber and a spring chamber adjacent said cap; a solenoid coil located in said solenoid chamber; a fixed core located internally of said coil; an armature extending into said solenoid chamber internally of said coil in opposing relationship to said core and extending outwardly of said solenoid chamber into said spring chamber through an opening in said disc; a guide member rigid with said armature in said spring chamber and engaging an opening in said cap whereby to prevent rotation of said armature about its axis; a flange interposed between said armature and said rigid member; a first coil spring interposed between said flange and said cap; a second coil spring interposed between said flange and said disc; said springs resiliently reacting to the vibrations of said armature; a number of patter rollers; a support for said rollers located outwardly of said casing and rigid with said guide member; each of said rollers being so mounted on said support as to be freely rotatable with respect thereto about an axis perpendicular to the direction of the vibrations of said armature; and means including said conductors for conveying an electric current through said coil.

3. A mechanical beauty aid, comprising a casing embodying a cylindrical member, a closure member rigidly connected to one end of said cylindrical member and having an opening therein for two conductors, and a cap rigidly connected to the other end of said cylindrical member; a disc rigidly mounted internally of said casing and dividing the space enclosed by said casing into a solenoid chamber and a spring chamber adjacent said cap; a solenoid coil located in said solenoid chamber; a sleeve rigidly attached to said disc, extending internally of said solenoid, and having a longitudinal slot therein and a flared open end; a core located internally of said sleeve, said core having a pin engaging seat slots in said sleeve to maintain said core in fixed positioned relationship to said sleeve; an armature extending into said solenoid chamber internally of said sleeve in opposing relationship to said core and extending outwardly of said solenoid chamber into said spring chamber through an opening in said disc; a polygonal guide member rigid with said armature in said spring chamber and freely engaging a matching polygonal opening in said cap whereby to prevent rotation of said armature about its axis; a flange interposed between said armature and said guide member; a first coil spring interposed between said flange and said cap; a second coil spring interposed between said flange and said disc; said springs resiliently react-

ing to the vibrations of said armature; a number of paster rollers; a support for said rollers located outwardly of said casing and rigid with said guide member; each of said rollers being so mounted on said support as to be freely rotatable with respect thereto about an axis perpendicular to the direction of the vibrations of said armature and in fixed positioned relationship to said guide member; and means including said conductors for conveying an electric current through said 10 coil; said flared end of said sleeve cooperating to maintain said means in assembled relationship.
